INITIAL BUTTON

Ralph Clinton Bangs, Providence, R. I., assignor
to Coro-Gram, Inc., New York, N. Y., a corpora-
tion of New York

Application September 2, 1936, Serial No. 99,076

8 Claims. (Cl. 24—113)

My invention relates to a new and improved initial button.

One of the objects of my invention is to provide an improved button which can be used on shirts and garments and all other wearing apparel, said button having an initial or other ornamental design member associated therewith.

Another object of my invention is to provide a simple and efficient device whereby the button can be readily and securely assembled with the initial member or the like.

Another object of my invention is to provide a button having a recess in the outer or fair side thereof so that the application of the initial or other ornamental member will conceal the thread which is used for attaching the button to a shirt or to any other garment.

Another object of my invention is to provide a button having a recess in its outer or fair side, said recess having an undercut groove at the base of said recess, so that an initial member or the like which has resilient projections can be snapped into position, and said initial member or the like will be securely held in position.

Whenever I refer to an initial member it is to be understood that I wish to include any ornamental member or device made of metal or other suitable material which can be snapped into position and which will be securely held in the button.

Referring to the annexed drawing, Fig. 1 is a sectional view of the assembled device, the button being shown with its outer or fair side at the bottom of Fig. 1.

Fig. 2 is a top plan view of Fig. 1, part of the representation of the button having been broken away, in order to show the parts more clearly.

Fig. 3 is a bottom plan view of Fig. 1, showing the outer or fair side of the button. It is to be understood that Fig. 1 is a sectional view on the line I—I of Fig. 3.

Fig. 4 is an inner plan view of the initial member or the like, separated from the button, showing the concave side of the initial member.

Referring to Fig. 1, this shows the button member 1, having the holes 2. Said button member 1 can be made of any suitable material, such as bone or metal, or the like. Said button member 1 is of the usual rigid construction. In the specific embodiment shown, said button 1 is provided with four holes 2 for receiving the sewing thread, but the invention is not to be limited in this respect.

As shown in Fig. 1, the outer or fair side of the button is provided with a recess 3. The configuration of said recess 3 is accurately shown in Fig. 1, and it will be noted that the base or inner end of said recess is provided with a groove whose wall 4 is of greater diameter than the adjacent wall-portion 5 of said recess. Hence the inner end of the longitudinal wall of the recess is undercut relative to the outer wall-portion of said recess. Said wall-portion 5 is substantially parallel to the longitudinal axis of the button. The outer end of said recess is provided with a tapered wall-portion 6.

The initial member 7 which is shown in Fig. 1 can be stamped out of metal or other suitable material, and this member is embossed or otherwise treated, so as to form an initial I or any suitable ornamental design or the like. In the particular embodiment illustrated herein, the initial is "C".

Said initial member 7 is formed with a sufficient number of integral depending lugs 7a which are of general concavo-convex or hook-like shape. In this particular embodiment there are six members 7a, which are preferably equally spaced. I can use any desired number of said members 7a.

The initial member is of general dome or arch shape as shown in Fig. 1, with its convex face outward.

The distance between the outer ends of the diametrically opposed tongues 7a of the initial member 7, when said tongues are unstressed, is greater than the diameter of the wall-portion 5. The tapered wall-portion 6 permits the initial member 7 to be readily forced into the mouth of the recess 3, as said tapered wall-portion causes the tongues 7a to be moved inwardly, so that they can enter that part of the recess which has the wall-portion 5.

Upon applying sufficient pressure, the tongues 7a can be moved into contact with and along the wall-portion 5, until the tongues 7a can spring outwardly so as to engage the undercut wall-portion 4 of the recess 3. The frictional grip and resilience of the tongues 7a are sufficient to hold the initial member 7 firmly in position.

However, since the hook-like members 7a are bent inwardly so that their convex surfaces abut the inner end of recess 3 and the inner wall thereof, the initial member 7 can be removed by applying a pin or other tool of small diameter through one or more of the holes 2,

whereby the initial member 1 can be forced out of the position shown in Fig. 1. Portions of the tongues 1a may be aligned with holes 2, or some of said holes. However, I prefer that 5 said tongues should not obstruct holes 2. That is, as shown in Fig. 1, the inwardly bent end portions of said tongues 1a can be short enough to clear the holes 2. While the tongues are integral with the initial member, the body of said 10 initial member is dome-shaped, so that it is rigid. The tongues 1a are shaped so as to make them resilient. By forcing the tool directly against the dome-shaped part of the initial, said initial can be removed without injuring the 15 tongues. Hence, the initials can be readily removed from the buttons, and then replaced. As shown in Fig. 1, the holes 2 are closer to the center of the button than the wall of recess 3, so that the holes are located inwardly, relative 20 to said wall. The convex walls of tongues 1a abut the inner end wall of recess 3 and said convex walls have substantially the same contour as the concave longitudinal section of wall 4 and the inner ends of said walls have the 25 same contour as the end-wall of recess 3, when member 1 is in position.

The outer surface of the initial member 1 may be flush with the outer end of the wall of the recess 3, or else the outer surface of the 30 initial member 1 may project above or be located below the outer end of the wall of said recess 3.

When used, the initial member 1 conceals the thread which has been passed through the holes 35 2, and which is used for securing the button 1 to the garment. As shown in Fig. 1, the member 1 is wholly within the lateral wall of recess 3, so that no part of member 1 projects laterally beyond the longitudinal wall of said 40 recess.

An ornamental effect is thus provided. Likewise, the retailer can keep a stock of the initials on hand, and readily apply said initials to the buttons, when a shirt or other garment is 45 sold. The buttons can be sewed to the shirt during the manufacture of the garment, in the ordinary manner, prior to applying the initials.

The invention is particularly useful for application to the cuff-buttons of shirts, as it provides means whereby said buttons can be ornamented, and the shirt can be identified.

The edge of the initial 1 may be slightly spaced from the wall-portion 5, or fit snugly in said wall-portion.

I have shown a preferred embodiment of my invention but it is clear that numerous changes and omissions can be made without departing from its spirit.

I claim:

60 1. In combination, a button made of rigid material and having holes for receiving sewing thread in the rear side thereof, said button having a recess at the fair side thereof, said holes opening into said recess, the longitudinal 65 wall of said recess having an undercut portion at its inner end, and a supplemental member removably held in said recess, said supplemental member substantially filling said recess and covering said holes, said supplemental member having spaced resilient tongues which engage said undercut portion of the wall of said recess, said tongues having inwardly directed convexo-concave shapes, the convex walls of said tongues 70 abutting the undercut portion of the wall of the 75

recess, and also abutting the inner end wall of said recess.

2. In combination, a button having holes for receiving sewing thread in the rear side thereof, said button being made of rigid material and having a recess at the fair side thereof, said holes opening into said recess and being laterally inwardly located relative to the longitudinal wall of said recess, the innermost portion of the longitudinal wall of said recess having a larger 10 diameter than the outer wall-portion of the longitudinal wall of said recess, and a supplemental member, which substantially fills said recess, said supplemental member having spaced resilient tongues resiliently engaging the innermost 15 wall-portion of the wall of said recess, said tongues having concavo-convex shapes, the convex walls of said tongues abutting said innermost portion and also abutting the inner end wall of said recess. 20

3. In combination, a button having holes for receiving sewing thread in its rear side, said button being made of rigid material and having a recess at the fair side thereof, said holes being laterally inwardly located relative to the longitudinal wall of said recess, the innermost portion of the longitudinal wall of said recess having a larger diameter than the outer wall-portion of the longitudinal wall of said recess, and a supplemental member which substantially fills 30 said recess, said supplemental member having spaced resilient tongues resiliently engaging the innermost wall-portion of the wall of said recess, said tongues having concavo-convex shapes, the convex walls of said tongues abutting the inner end wall of said recess, the tips of the free 35 ends of said tongues being laterally further away than said holes from the central longitudinal axis of the button, the innermost portions of said tongues abutting the inner end wall of said recess 40 and having substantially the same longitudinal contour as the longitudinal contour of the innermost wall-portion of the wall of the recess.

4. In combination with a solid button having the usual thread holes and adapted to be used 45 as a conventional button, the top surface of which is counter-sunk to provide a central cavity spaced a substantial distance from the edges of the button wherein the sewing threads may be located, the said thread holes opening through 50 the bottom surface of the button and piercing the bottom of the said counter-sunk cavity, a metal insert upon the top surface of which insignia may be impressed, received in the said cavity of the button, adapted to transform the 55 said conventional button into a composite button comprising the said button and the said metal insert, the said transformed button presenting a top face bordering the centrally located, insignia bearing metal insert, and means on the 60 insert for removably holding the same in the said counter-sunk cavity of the button and in spaced relation to the bottom of the cavity whereby the said metal insert may be attached to the button to transform it into said composite 65 button and whereby the said metal insert may be removed from the composite button to transform the latter into the conventional button.

5. A cap member adapted to be attached to a body member, such as a button or the like, the 70 exposed face of which is provided with a cavity having undercut peripheral edges, said cap member being provided with a plurality of prongs receivable in the said cavity of the body member, the outside diameter of the cap member at 75

- its said prongs being greater than the diameter of the said cavity at the exposed face of the said body member whereby the said prongs will underlie the said undercut edge of the cavity, 5
 5 the said prongs comprising an outwardly inclined portion dependent from the cap member and an inwardly inclined portion, the said outside diameter of the cap member being measured at the intersection of the two said portions
 10 and the diameter of the cap at the distal end of the said inwardly inclined portion being smaller than the said diameter of the cavity of the body member whereby the cap member will be guided into position in the cavity of the body
 15 member.
6. In combination with a bone button having the usual thread holes and adapted to be used as a conventional all-bone button, the top surface of which is counter-sunk to provide a central cavity spaced a substantial distance from the edges of the button wherein the sewing threads may be located, the said thread holes opening through the bottom surface of the button and piercing the bottom of the said counter-sunk cavity, a metal insert upon the top surface of which insignia may be impressed, received in the 10 said cavity of the bone button, adapted to transform the said conventional all-bone button into a composite button comprising the said bone button and the said metal insert, the said transformed button presenting a bone face bordering 15 the centrally located, insignia-bearing metal insert, and means on the insert for removably holding the same in the said counter-sunk cavity of the bone button, comprising an element depending from the insert and seated on the bottom of 20 the cavity, whereby the said metal insert may be attached to the bone button to transform it into the said composite button and whereby the said metal insert may be removed from the composite button to transform the latter into the 25 conventional all-bone button.
7. In combination with a bone button having
- 20
- 25
- 30
- 35
- 40

the usual thread holes and adapted to be used as a conventional all-bone button, the top surface of which is counter-sunk to provide a central cavity spaced a substantial distance from the edges of the button wherein the sewing threads may be located, the said thread holes opening through the bottom surface of the button and piercing the bottom of the said counter-sunk cavity, a metal insert upon the top surface of which insignia may be impressed, received in the 10 said cavity of the bone button, adapted to transform the said conventional all-bone button into a composite button comprising the said bone button and the said metal insert, the said transformed button presenting a bone face bordering 15 the centrally located, insignia-bearing metal insert, and means on the insert for removably holding the same in the said counter-sunk cavity of the bone button, comprising an element depending from the insert and seated on the bottom of 20 the cavity, whereby the said metal insert may be attached to the bone button to transform it into the said composite button and whereby the said metal insert may be removed from the composite button to transform the latter into the 25 conventional all-bone button.

8. In combination, a button having holes for receiving thread in its rear wall, said button having a recess at the fair side thereof defined by an inner end wall and a longitudinal wall, said holes 30 opening into said recess, and a supplemental dome-shaped removable member having resilient means which abut the inner end wall of said recess and which releasably engage the longitudinal wall of said recess, said dome-shaped member 35 substantially filling said recess, the maximum diameter of the said recess being at least as great as the maximum lateral dimension of said supplemental member, the said supplemental member having no part thereof overhanging the 40 longitudinal wall of said recess.

RALPH C. BANGS.
